HERBERT STUART INDGE, OF WESTBORO, MASSACHUSETTS, ASSIGNOR, BY MESNE ASSIGNMENTS, TO NORTON COMPANY, OF WORCESTER, MASSACHUSETTS, A CORPORATION OF MASSACHUSETTS

INTERNAL LAPPING MACHINE

Application filed June 6, 1927. Serial No. 196,947.

This invention relates to a machine for lapping or honing internal surfaces such as the inner walls of rings, collars or bearings. It is an important object of my invention to provide a machine for such purposes in which a rotatable lap may be caused to repeatedly traverse an internal surface axially, preferably while yieldingly engaged therewith.

Another object is to provide a machine in which the lapping operation will be automatically discontinued after a predetermined number of axial traverses of the lap over the internal surface.

A further object of the invention is to provide means for presenting a new piece of work in position for lapping, such presentation being also preferably automatic.

Important features of the invention relate to the provision of a work holder which will align itself with the rotating lap, and to the provision of an improved form of lap which automatically expands to the size of the hole to be lapped but which may be quickly and easily contracted for removal or insertion in the work.

My invention further relates to arrangements and combinations of parts which will be hereinafter set forth and more particularly pointed out in the appended claims.

A preferred form of the invention is shown in the drawings in which

Fig. 1 is a side elevation of my improved lapping machine, with certain parts shown in section;

Fig. 2 is a front elevation thereof;

Fig. 3 is an enlarged sectional side elevation of the lower portion of the machine, showing the driving mechanism;

Fig. 4 is a similar view of the upper portion of the machine;

Fig. 5 is a partial sectional rear elevation, taken along the line 5—5 in Fig. 4;

Fig. 6 is an enlarged front elevation, partly in section, showing the lower end of the lapping spindle and the expanding lap mounted thereon;

Fig. 7 is a sectional plan view, taken along the line 7—7 in Fig. 6 and showing the lap contracted;

Fig. 8 is a similar view, showing the lap expanded;

Fig. 9 is a sectional plan view, showing a slightly modified construction;

Fig. 10 is a plan view of the upper ends 55 of the lapping elements, with the expansion rod or plunger shown in section;

Fig. 11 is a side elevation of the lap driving sleeve;

Fig. 12 is a detail sectional elevation, taken 60 along the line 12—12 in Fig. 6;

Fig. 13 is a partial front elevation, partly in section, showing the lapping head and the mechanism for contracting and expanding the lap;

Fig. 14 is a front elevation of the mechanism for raising and lowering the work table;

Fig. 15 is a sectional plan view of the intermittent table feed, taken along the line 15—15 in Fig. 3;

Fig. 16 is a sectional rear elevation of the mechanism for controlling the duration of the lapping operation, taken along the line 16—16 in Figs. 3 and 4;

Fig. 17 is a view similar to Fig. 16 but 75 showing the parts in a different position;

Fig. 18 is a sectional rear elevation of certain clutch mechanism, taken along the line 18—18 in Fig. 3; and

Figs. 19 and 20 are similar views, showing 80 the operation of certain parts of the clutch.

Referring to the drawings, I have shown a lapping machine comprising a frame 30 (Fig. 1) having a horizontal work table 40 rotatable in a guard or casing 31 and having a lapping head 32 reciprocated within a casing 33 secured to a standard 34 forming an upper portion of the frame 30.

A motor M is mounted on a bracket 34 90 projecting rearwardly from the frame 30, said motor being connected by a belt or chain 35 and pulley or sprocket 36 to a main drive shaft 37 rotatable in suitable bearings in the lower portion of the frame 30.

The work table 40 (Fig. 3) is normally maintained in raised or operative position, but mechanism is provided for intermittently lowering the table 40 and for intermittently advancing the table angularly to pre- 100

sent a new piece or pieces of work in position for the lapping operation.

Timing mechanism is provided for advancing the work table angularly after any desired number of axial traverses of the lap within the work, and mechanism is also provided for contracting the lapping elements before the work table is moved downward to withdraw a finished piece of work and to present a new piece of work in place thereof. Mechanism is also provided for vertically reciprocating the lapping spindles and for continuously rotating the spindles.

I will now proceed to describe in detail the several mechanisms above outlined.

Lapping spindle and drive

One or more lapping spindles 50 (Fig. 2) are mounted in bearings 51 and 52 (Fig. 4) secured to the standard 33 of the frame 30. A bevel gear 53 is keyed to the central lower lapping spindle, but permits the spindle to slide freely therethrough. The gear 53 is engaged by a bevel pinion 54 secured to the front end of a cross shaft 55 supported in fixed bearings 56 and 57 in the standard 33 and having a pulley or sprocket 58 fixed to the rear end thereof and connected by a belt or chain 59 to a pulley or sprocket 60 on the drive shaft 37 (Fig. 3). By these connections, the spindle 50 is continuously rotated.

If a plurality of spindles is used, a gear 61 (Figs. 4 and 13) is fixed on the spindle 50 and engages similar gears 62 on the side spindles 50^a and 50^b, thus rotating the spindles simultaneously.

A grooved collar 65 (Fig. 4) is fixed to the spindle 50 and is engaged by rolls 66 (Fig. 13) on the forked front end of a lever 67 (Fig. 4) pivoted on a stud 68 fixed in the standard 33. If three spindles are used, additional collars 65^a (Fig. 13) are provided on the outer spindles and additional rolls 66^a are provided on the outer faces of the lever 67 to engage the collars 65^a.

The lever 67 is provided with a plurality of holes 69 and the standard 33 is provided with corresponding holes, so that the stud 68 may be inserted in different positions to 50 vary the proportions of the lever 67 and thus vary the reciprocation of the lapping spindle 50.

A link 70 is pivoted at 71 to the rear end of the lever 67 and is also pivoted at 72 on a cross shaft 73 (Fig. 5) which extends through a slide plate 74. The ends of the shaft 73 extend at each side of the plate 74 and provide supports for weights 75 which counterbalance the spindles 50 where a plurality of spindles is used.

The slide plate 74 is provided with a pair of cam rolls 77 (Fig. 5) adapted to engage a cam 78, detachably connected by a stud 79 (Fig. 4) to a gear 80 rotatable upon a fixed stud 81 projecting rearward from a support

within the standard 33. The gear 80 is engaged by a pinion 82 on the cross shaft 55 previously described.

The slide plate 74 (Fig. 5) is mounted in suitable guide-ways 83 on the standard 33 and is vertically reciprocated by the connections above described. Ordinarily the weights 75 are sufficient to somewhat overbalance the spindles 50 so that the upper rolls 77 continuously engages the rotating cam 78. If, however, the spindles should overbalance the weights, or the slide plate should stick, the lower roll 77 then becomes operative and the slide plate is similarly reciprocated under either condition. The cam 78 is so designed that the spindles will have a continuous reciprocation, without appreciable dwell at the reversals, thus avoiding the production of bell-mounted holes.

Lap construction

I have provided a special form of lap for use in my improved machine, involving important features of construction and operation which will now be described.

The lap is formed of a plurality of lapping elements 90 (Figs. 6 to 8), preferably three in number, which may be made by cutting a cylindrical or conical lap longitudinally into three pieces. The lower ends of the lapping elements are reduced in diameter as indicated as 91 (Fig. 6) and are provided with inclined portions 92 adapted to readily guide the lapping elements into the hole to be lapped.

An annular spring 93 is fitted in a groove 94 in the lower ends 91 of the lapping elements and holds said elements contracted as shown in Fig. 7, except when they are forcibly expanded by means to be described.

At their upper ends, the lapping elements 90 are provided with flanges 95 engaged by an internal annular flange 96 formed at the lower end of a cap or collar 97 threaded onto each lapping spindle 50, 50^a or 50^b. Each flanged portion 95 of a lapping element is also provided with a slot or recess 98 adapted to receive a lug or projection 99 (Fig. 11) formed on the lower end of a sleeve 100.

In assembling the parts, the lapping elements 90 are inserted from above in the circular opening 101 of the cap 97, and the sleeve 100 is then inserted in the opening 101, with the projections 99 extending into the slots 98, thus providing guides for the radial movement of the expanding lapping elements 90 and holding them in angularly spaced relation. The projections 99 are preferably of greater length than the thickness of the flanges 95. A second annular coil spring 102 may be provided near the upper ends of the lapping elements 90 to contract the same as previously described.

On their inner surfaces, the lapping ele-

ments are provided with tapered or conical bearing surfaces 103 (Fig. 6) engaged by the tapered lower end 104 of an expansion rod or plunger 105 slidable longitudinally in an axial opening of the spindle 50. As the plunger 105 is pushed downward, thelapping elements 90 tend to expand against the tension of the annular springs 93 and 102.

At the upper end of each spindle 50, 50^a or 50^b (Fig. 4) each plunger 105 extends through a forked lever 106 and is threaded to receive lock nuts 107 forming a shoulder or abutment for said lever. The levers are mounted on fixed pivots 108 in the stand 33 and are intermittently lifted by operating mechanism to be described.

A coil spring 110 is mounted on the upper end of each plunger 105 and is positioned between a washer 112 and pin 113 on the plunger 105 and a cap 114 threaded or otherwise secured on the upper end of the spindle 50. The spring thus acts to yieldingly force the plunger 105 downward and is of sufficient strength to overcome the tension of the annular springs 93 and 102. Each spring 110 may be adjusted by screwing its cap 114 on or off of the end of its spindle 50.

In Fig. 9 I have shown a slight modification in which the lower end of the plunger 105 is of triangular tapered cross section, as indicated at 115, and thelapping elements 116 are provided with similar flat inclined surfaces 117. The operation is substantially the same as that above described, except that relative angular movement of the plunger 105 andlapping elements 116 is prevented.

It will be noted, that inasmuch as the laps are expanded by a cam or wedge of comparatively slight taper, the spring is able to push the laps apart and so fill the hole in the work, but the reverse is not possible. In other words, the ovality or other error in the hole cannot make the lap yield or "sponge" as in the case of a simple spring expanded lap.

Attention is also directed to the fact that the laps are so guided and expanded as to partake of a strictly radial movement, during which all parts of each lap maintain parallelism with the remaining laps.

50 Work holders and table

I have provided special work holders mounted on the work table 40 and adapted to freely align themselves with the rotating lap.

55 A preferred construction of the work holders is shown in Fig. 3, in which the work W is secured by clamping plates 120 in a ring or holder 121 which is provided with studs or trunnions 122 pivoted in lugs 123 extending upward from a base or stand 124 adapted to be clamped or otherwise secured to the work table 40. The ring or holder 121 is free to slide transversely along the axis of its trunnions 122 and is also free to rock on said trunnions. As the lap descends, it moves

the work into alignment with the axis of the lap, the holder adjusting itself laterally and angularly on its trunnions 122 as may be necessary for exact alignment with the lap.

The work table 40 (Fig. 3) is fixed to the upper end of a supporting rod 125 slidable in a bearing 126 in the frame 30. The work table is also provided with edge recesses 127 adapted to receive a guide-roll 128 mounted on the casing 31, said roll accurately positioning the table angularly and holding the table from angular movement during thelapping operation. When the table is lowered, as will be hereinafter described, the recesses 127 are below the roll 128, thus permitting free rotation of the table.

A cam roll 130 (Figs. 3 and 14) is pivoted in a member 131 mounted on a stud 132 rotatably seated in an axial recess in the lower end of the supporting rod 125. The cam roll 130 is engaged by a cam 133 mounted on a cross shaft 134 rotatable in bearings in the lower part of the frame 30 and having a bevel gear 135 engaging a second bevel gear 136 fixed to the lower end of an upright shaft 137, 90 also rotatable in fixed bearings in the frame 30.

The shaft 137 is connected by bevel gears 138 and 139 to a horizontal cross shaft 140 rotatable in fixed bearings in the base 30. 95 The shaft 140 is intermittently given a single revolution by clutch mechanism to be described and when thus actuated, the cam 133 is also given a single rotation, lowering the work table from operative position and thereafter raising the same to operative position.

Table feeding mechanism

For the purpose of giving the work table 40 an intermittent angular movement to advance new pieces of work successively to laps position, I provide a member 142 (Figs. 3 and 15) on the work-supporting shaft 125, said member being provided with a plurality of radially extending grooves 143. When the work table is in its lower position, the grooves 143 are positioned for engagement by a roll 145 mounted on an arm 146 (Fig. 3) secured to the intermittently rotated shaft 137 previously described. The roll 145 (Fig. 115 15) enters the radial grooves or slots 143 in progressive order and each time advancing the work table 90°, the action being equivalent to the usual Geneva stop motion.

As the table is raised from its lower position, the roll 128 (Fig. 3) on the casing 31 enters one of the vertical slots 127 in the periphery of the work table and thus accurately centers the table and holds the same from rotation during thelapping operation. 125

Lap release mechanism

Special devices are provided for allowing thelapping elements 90 to contract before the work table 40 is lowered and permitting 130

them to remain contracted until the table is returned to its operative or raised position. For this purpose the levers 106 (Fig. 4) previously described are engaged by a cross bar 150 adjustably positioned at the upper end of vertically sliding rods 151 (Fig. 13). The rods 151 extend downward through bearing sleeves 152 (Fig. 3) and are provided at their lower ends with a cross head 154 having a cam roll 155 engaging a cam 156 on the intermittently rotated shaft 140.

The cam is so timed that the cross bar 150 and levers 106 will be raised during the lowering and feeding of the work table, thus 15 raising the plungers 105 (Fig. 6) within the lapping spindles and withdrawing their tapered ends 104 from engagement with the lapping elements 90. As the table returns to operative position, the plungers or rods 20 105 are released and are allowed to move downward, under the pressure by the springs 110 (Fig. 4).

Timing mechanism

25 The shaft 140 is normally stationary but is given a single revolution at predetermined intervals to lower and feed the work table and to collapse and expand the lap as previously described.

30 The mechanism for determining the duration of the lapping operation is best shown in Figs. 3, 4 and 16 to 20. A cam 160 (Fig. 16) is normally connected by a stud 161 (Fig. 3) to rotate with a gear 162 loosely mounted 35 on the shaft 140 and connected by a pinion 163, gear 164 and pinion 165 to the main drive shaft 37. The cam 160 is thus continuously rotated, but at greatly reduced speed.

30 The cam 160 is preferably double-acting, as indicated in Fig. 16, and engages a cam roll 166 on the lower end of a bent lever 167, swinging on a fixed pivot 168. The lever 167 is slotted at 169 to receive a pin 170 in the side of an arm 171, having a feed pawl 172 (Fig. 17) at its outer end. The feed pawl 172 engages a ratchet wheel 173 loosely mounted on a stud 174 (Fig. 4) which also supports the arm 171.

50 A holding pawl 175 (Fig. 17) is mounted on an arm 176 also pivoted on the stud 174 and connected to a link 177 at its upper end. The link 177 is threaded to receive an adjusting nut 178 on the outside of the standard 33 and a spring 179 is mounted on the link 177 between a pin 180 on the link and a washer 181 engaging the inside of the casing 33.

55 An arm 183 (Fig. 17) is connected to move with the arm 176 about the axis of the stud 174 and is provided with a shield 184 which 60 may be moved toward or away from the feed pawl 172 by adjustment of the nut 178.

As the feed pawl 172 has a constant stroke, the rate of feed may be varied by changing the position of the shield 184, so that more 65 or less teeth on the ratchet will be uncovered

for engagement on rearward movement of the feed pawl.

A lug or projection 185 is fixed on the side of the ratchet wheel 173 and is gradually advanced by the feeding of the ratchet until it engages a projection 187 (Fig. 16) projecting laterally from a rod 188 slidable in fixed bearings 189. The rod 188 extends freely through a collar 190 (Fig. 18) which is connected by a link 191 to an arm 192 by which a one-revolution clutch of commercial form is controlled.

The normal position of the clutch parts is as shown in Fig. 19, in which a roll 193 is seated in the recess 194 of a fixed plate 195 and is also positioned in a similar recess 196 (Fig. 20) of a second plate mounted for movement about the axis of the fixed plate 195 and having the arm 192 projecting therefrom.

The roll 193 is mounted on a lever 198 pivoted at 199 on a split expanding band 200 surrounding the cylindrical hub 201 (Fig. 3) of the cam 160. A shoulder 202 (Fig. 18) on the arm or lever 198 engages the end 203 of a notch or recess in a bolt 204 extending through 90 an opening in the offset end 205 of the split band 200, said bolt having adjusting nuts 206 threaded thereon.

If the collar 190 (Fig. 18) is moved upward, it will act through the link 191 to swing 95 the arm 192 and its associated cam plate about the axis of the clutch mechanism, bringing the recess 196 (Fig. 20) out of alignment with the recess 194, thus forcing the roll 193 outward, swinging the arm or lever 198 and tightening the split band 200 about the continuously rotating hub 201 of the cam 160.

The shaft 140 will thus be rotated for a single revolution, until the notch 196 returns to alignment with the recess 194. Upon thus completing the revolution, the roll 193 will drop into the aligned recesses 194 and 196 and the shaft will again come to rest. The one-revolution clutch mechanism above described in itself forms no part of my invention and any other suitable one-revolution clutch may be substituted therefor.

The collar 190 (Fig. 17) is loose on the rod 188 and is normally held from vertical movement by a latch 210 mounted on a fixed pivot 211. A spring 212 is mounted on the lower end of the rod 188 between the collar 190 and a pin 213 at the lower end of the rod.

When the projection 187 on the rod 188 is engaged by the lug 185 on the ratchet wheel, 120 the rod 188 is moved upward, compressing the spring 212, while the collar 190 remains locked by the latch 210. A cross pin 214 on the rod 188 eventually engages the latch 210, as the rod 188 reaches its upper position, 125 thus unlocking the collar 190 and allowing the same to slide quickly upward, swinging the arm 192 and rendering the one-revolution clutch operative.

The parts are so timed that the lug 185 130

will clear the projection 187 as the latch 210 is released, so that the rod 188 and collar 190 return to their normal lowered positions as shown in Fig. 17 before the single revolution of the shaft 140 has been completed. A weight 215 (Fig. 16) is provided to expedite the return movement and a handle 216 is provided for manual control of the clutch.

If it is desired to prolong the lapping operation, the shield 184 is moved upward by the adjusting nut 178 so that less teeth will be uncovered on the rearward movement of the feed pawl, and if it is desired to shorten the lapping operation, the shield is moved downward to uncover more teeth.

Operation

Having thus described in detail the mechanism of my improved lapping machine, the general operation thereof is as follows:

The rings or collars or other similar pieces of work $\bar{W}$ are first mounted in the work holders 121 and one of these holders is aligned with the lap. The machine is then started in operation, rotating the lap within the hole in the work and yieldingly forcing the lapping members 90 outward against the cylindrical inner wall of the work until the desired size and finish has been attained. The duration of the lapping operation is regulated by the setting of the shield 184 (Fig. 17) by the adjusting nut 178. At the end of a predetermined period, the one-revolution clutch is released and rotates the shaft 140 (Fig. 3) through a single complete revolution.

This rotation of the shaft 140 accomplishes several related purposes. In the first place, the cam 133 is rotated to lower the work table 40 away from the fixed guide roll 128. At the same time, the cam 156 raises the expanding plungers 105 within the laps, allowing the lapping elements to contract during the lowering of the work table, and the presentation of a new piece of work. As the work table 40 approaches its lower position, the roll 145 engages one of the slots in the disc member 143, advancing the table 90° .

The cam 133 then returns the work table 40 to operative position and the cam 156 releases the lap-expanding plungers. All of these movements are completed during the single revolution of the shaft 140, which comes to rest as soon as the single revolution is completed.

During this removal and replacement of the work, the lapping spindles 50 have continued to rotate and the slide plate 74 has continued its reciprocation, raising and lowering the laps in their usual manner.

The machine is thus entirely automatic in its operation and it is merely necessary for the workman to remove the finished pieces of work and replace the same with new pieces

in the work holders which are out of operative position.

If a plurality of lapping spindles are used, as indicated in Fig. 2, it will be understood that a corresponding number of work holders 70 will be provided on each quarter section of the work table.

Having thus described my invention and the advantages thereof, I do not wish to be limited to the details herein disclosed otherwise than as set forth in the claims, but what I claim is:—

1. In a lapping machine, a lapping spindle, a lap comprising a plurality of depending lapping elements mounted on said spindle, automatically operated means to expand and contract said lapping elements, and a positive driving connection between said spindle and each lapping element. 80

2. A lapping machine comprising a lapping spindle, means to rotate said spindle, means to reciprocate said spindle, a lap comprising a plurality of depending lapping elements mounted on said spindle, automatically operated means to expand and contract said lapping elements during the spindle reciprocation, and a positive driving connection between the spindle and each lapping element. 90

3. A lapping machine comprising an expandable lap, mechanism arranged to rotate said lap, means to reciprocate said lap relative to and within a cylindrical internal work surface and automatically actuated means independent of the reciprocating means to yieldingly expand said reciprocating lap from an inoperative to an operative position after the lap has been entered into the work piece to be lapped. 95

4. A lapping machine comprising an expandable lap, means to rotate said lap, mechanism to reciprocate the lap and independently actuated, automatically operated means synchronized with the reciprocating mechanism to expand said lap against a cylindrical internal surface to be lapped after it has been inserted within the work.

5. A lapping machine comprising an expandable lap, a support for work having an internal cylindrical surface to be lapped, means to rotate said lap, mechanism to axially reciprocate the lap in operative contact within the work, and means to contract said lap and remove it from contact with the work surface after a predetermined number of lap reciprocations.

6. An internal lapping machine comprising a lap, means to rotate said lap, means to axially reciprocate said lap relative to a piece of work having a cylindrical hole therein, automatic means synchronized with said reciprocating means to separate said lap and work after a pre-determined number of reciprocations of said lap, and means synchronized with said automatic means to auto-

matically remove the work from lapping position and to present a new piece of work in lapping position.

7. In a lapping machine, a lap comprising a plurality of lapping elements, means to rotate and axially reciprocate said lap, a work holder, means to cause said work holder and lap to approach and separate, and automatic means synchronized with said last named means to expand said lap on an approach movement of said parts and to contract said lap on a movement of separation of said parts.

8. A lapping machine comprising a lap having a plurality of lapping elements, means to rotate and axially reciprocate said lap within a cylindrical internal work surface to be lapped, a work holder, means to cause said work holder and lap to approach and separate after a predetermined number of lap reciprocations to withdraw the lap from the work, and means acting in synchronism with said last named means to expand said lap on an approach of said parts and to contract the lap on a separation movement of said parts while the lap is within the work.

9. A lapping machine comprising an expandible lap, a support for work having an internal cylindrical surface to be lapped, means to rotate the lap, mechanism to axially reciprocate the lap within the work, means acting in timed relation with the lap reciprocation whereby the lap may be expanded and contracted at predetermined positions of the lapping tool relative to the work, and means to maintain said lap in an expanded position to cause it to engage the work for a predetermined number of lap reciprocations.

10. A lapping machine comprising a stationary frame, a spindle mounted thereon, means to rotate said spindle, means to reciprocate the spindle, a lapping tool mounted upon one end of said spindle which is provided with expandible abrading elements, a cam rotatably mounted within the stationary frame, means to rotate the cam in timed relation with the spindle reciprocation, and connections between said cam and the expandible elements whereby they may be expanded and contracted at predetermined positions of said tool reciprocation and maintained in an expanded position for a predetermined number of tool reciprocations.

11. In a lapping machine, a lap comprising a plurality of lapping elements, means to rotate and axially reciprocate said lap, a work holder, means to cause said work holder and lap to approach, and to thereafter axially separate after a predetermined number of reciprocations of said lap, and means synchronized with said last named means to expand said lap on an approach movement of said parts and to contract said lap on a movement of separation of said parts.

12. A lapping machine comprising an ex-

pansible lap, a work support, means to rotate the lap, means to axially reciprocate the lap within a cylindrical internal work surface, automatic mechanism to axially separate the lap from the work after a predetermined number of lap rotations, automatic means associated therewith and acting in timed relation with the lap reciprocation to expand the lap after insertion within the work and to contract the lap upon completion of a predetermined lapping cycle but prior to its removal from the work.

13. In a lapping machine, a lap comprising a plurality of lapping elements, means to rotate and axially reciprocate said lap, a work table, work holders thereon, means to cause said work table and lap to approach, and to thereafter axially separate after a predetermined number of reciprocations of said lap, and means synchronized with said last named means to expand said lap on an approach movement of said parts and to contract said lap on a movement of separation of said parts and means to advance one of said work holders to lapping position during the separation of said table and lap.

14. In a lapping machine, an expandible rotatable lap, a rotatable work table, an actuating shaft, means to give said shaft a single revolution at predetermined intervals, and means actuated by said shaft to withdraw said lap expanding means and permit the lap to contract, to axially separate said lap and work table, to angularly advance said table, and to thereafter restore said table and lap to operative relation and to expand said lap.

15. In a lapping machine, a lapping spindle having a grooved collar thereon, a lever engaging said collar, a slide plate, a link connecting said slide plate to said lever, spaced cam rolls on said slide plate, and a cam continuously rotating between said rolls to reciprocate said lapping spindle.

16. In a lapping spindle, means to rotate said spindle, means to reciprocate said spindle, a cap on the lower end of said spindle having an internal angular lower flange, a plurality of depending lapping elements each having an outer flange at its upper end cooperating with said angular inner flange to attach said lapping elements to said spindle, means to prevent relative angular movement between said spindle and said lapping elements, and means synchronized with said rotating and reciprocating means to expand said elements.

17. A lapping machine comprising a reciprocable member, a spindle rotatably mounted on said member, a lapping tool carried by the spindle and provided with expandible grinding elements, an expanding member therefor, and means for actuating the expanding member to maintain the grinding elements in operative engagement

with the work during a predetermined number of movements of said member.

18. A lapping machine comprising a reciprocable member, a spindle rotatably mounted on said member, a tool carried by the spindle provided with expansible grinding elements and means for expanding said grinding elements during a predetermined number of movements of said reciprocable member, said means including means for collapsing the grinding elements at the completion of said movements.

19. A lapping machine comprising a frame and mechanism supported thereon so as to be reciprocable, a plurality of spindles rotatably mounted in said mechanism, tools carried by said spindles provided with expansible grinding devices, control devices for said tools also carried by said spindles which hold said tools normally in collapsed position, means for independently operating said control devices, and mechanism for imparting movement to said last named means to cause a simultaneous expansion of all of said grinding devices during the operation of said first named mechanism.

20. In combination with a stationary frame and frame mounted thereon so as to reciprocate, a spindle rotatable in said last-named frame, a grinding tool on the end thereof, provided with expansible abrading elements, a rod in said spindle operatively connected with said abrading elements, a rocker-arm for engagement with said rod, means for imparting intermittent movements to said rocker-arm, to properly actuate said rod, and means for adjustment of the position of said rod with reference to the rocker-arm.

21. A lapping machine comprising a main frame and mechanism supported thereon, a plurality of spindles mounted for simultaneous rotation and reciprocation by said mechanism, tools carried by said spindles provided with expansible lapping members, control devices for said tools carried by the spindles, means acting in timed relation with the tool reciprocation to maintain said tools in a collapsed position when withdrawn from the work and to expand the tools into contact with the work after insertion therein, and yielding means cooperating therewith to cause an expansion of the laps as the lapping operation proceeds.

22. A lapping machine comprising a stationary frame, a support mounted thereon so as to reciprocate, a spindle rotatably mounted in said frame and arranged to reciprocate with said support, an expansible grinding tool fastened to one end of the spindle and provided with radially movable abrading members, an axially movable rod within said spindle operatively connected with the abrading members to cause them to simultaneously and yieldingly move into engagement with a cylindrical internal work surface, a rocker

arm arranged to engage said rod, mechanism acting in timed relation with the spindle reciprocation for imparting cyclic movement to the rocker arm and thereby positioning each of the abrading members in positive engagement with the internal work surface during a predetermined number of spindle reciprocations, and means for adjusting the position of said rod relative to the rocker arm.

23. In combination with a main frame and mechanism supported thereon so as to be reciprocable, a plurality of spindles rotatably mounted in said mechanism, tools carried by said spindles, provided with expansible grinding devices, control devices for said tools, also carried by said spindles, holding said tools normally in collapsed position, means for the independent operation of said control devices, and mechanism for imparting movement to said last-named means to cause a gradual expansion of all of said tools during the operation of said first-named mechanism, and means for withdrawing said expanding member to permit the collapse of said grinding elements at the end of said pre-determined number of reciprocations.

24. In a honing machine, the combination of an expansible honing tool, means for rotating said tool, means for shifting said tool into and out of the work and for reciprocating said tool within the work, means for expanding and contracting said tool, and means automatically operable during the shifting of said tool to actuate said last named means to thereby free said tool from the work during insertion and extraction therefrom.

25. In a honing machine, the combination of an expansible honing tool, means for rotating said tool, means for shifting said tool into and out of the work and for reciprocating said tool within the work, means for expanding and contracting said tool, and cam controlled means automatically operable during the shifting of said tool to actuate said last named means.

In testimony whereof I have hereunto affixed my signature.

HERBERT S. INDGE.
